(57) **CLAIM**

The ornamental design for a bone plate, as shown and described.

DESCRIPTION

FIG. 1 is a top perspective view of a bone plate comprising the new design;

FIG. 2 is a right elevational view of the design of FIG. 1;

FIG. 3 is a left elevational view of the design of FIG. 1;

FIG. 4 is a top view of the design of FIG. 1;

FIG. 5 is a bottom view of the design of FIG. 1;

FIG. 6 is a front elevational view of the design of FIG. 1; and,

FIG. 7 is a rear elevational view of the design of FIG. 1.

The broken lines shown in the figures are directed to the environment and are for illustrative purposes only; the broken lines form no part of the claimed invention.

1 Claim, 2 Drawing Sheets
